ATTORNEY

UNITED STATES PATENT OFFICE.

FOSTER W. DRAPER, OF SPOKANE, WASHINGTON.

FURNITURE JOINT.

Application filed March 19, 1923. Serial No. 625,941.

To all whom it may concern:

Be it known that I, FOSTER W. DRAPER, a citizen of the United States, residing at Spokane, in Spokane County, and State of 5 Washington, have invented certain new and useful Improvements in Furniture Joints, of which the following is a specification.

My present invention relates to improvements in furniture joints and particularly to 10 the fastening means for chairs and similar articles of furniture, wherein it is necessary to make a rigid and permanent joint between two connecting members. While I shall hereinafter refer to the invention as 15 applied to chair joints, it will be understood that the invisible fastening means of my invention may with equal efficiency be used in the construction of other articles of furniture.

20 The primary object of my invention is the provision of an invisible and permanent fastening means, which is comparatively inexpensive in cost of production, but is capable of retaining the joined members of 25 the piece of furniture in rigid relationship and well adapted to withstand wear and use. The invention consists in certain novel combinations and arrangements of parts as will hereinafter be described and claimed.

30 In the accompanying drawings I have illustrated several forms of one of the fastening members which is combined with the anchoring device of the fastening means, showing the physical embodiment of the 35 principles of my invention.

The invisible fastening means may be used 40 to join a chair leg and chair round, or it may be used to join the leg to the seat of a chair, and the fastening means is readily adapted for use with numerous joints involving a mortise or socket and tenon joint, as hereinafter set forth.

Figure 1 is a perspective view of an anchoring key of tubular construction, having 45 split ends, and adapted to be secured in the tenon member of the joint.

Figure 2 is a sectional detail view showing a mortise and tenon joint, as between the leg and round of a chair, in which the 50 joining process is partly completed.

Figure 3 is a perspective view of the cap used with the anchoring key.

Figure 4 is a detail sectional view showing a completed joint and the fastening 55 members in use.

Figure 5 is a perspective view of a modified form of fastening cap.

Figure 6 is a detail sectional view showing the cap of Figure 5 in use with the anchoring key of Figure 1. 60

Figure 7 is a further modified form of the fastening cap for use with the anchoring key.

For convenience of description and illustration of my invention, it will be assumed 65 that the member 1 may be a chair leg having the usual mortise or socket 2, and one of the rounds of the chair is indicated at 3 and provided with a tenon-end 4.

The anchoring key 5 of the fastening 70 means is a tube of suitable metal of proper length and diameter to adapt it for use and may be of various sizes for use in a variety of styles or sizes of furniture. At its ends the tube is slit or split longitudinally as 75 at 6 and 6', and these slits form a plurality of expandible tongues 7 which are adapted to be forced outwardly or spread, under pressure, as indicated at 7' in Figure 4. To insure a spreading movement of these 80 tongues as the slit end of the anchoring key is forced into the tenon of the round 3, the edges at the ends of the tube are beveled at their inner sides, as at 8. These beveled 85 portions, when the anchoring tube is forced by suitable power into the tenon 3, (which may be counterbored if necessary), to cause the tongues 7' to spread or turn out and provide a rigid anchor in the wood for the 90 key.

In Figures 2, 3, and 4 the fastening cap 9 is in the form of a circular disk with a central opening 10 in order that it may be slipped over the anchoring key and welded or brazed, or rigidly secured thereon in 95 other suitable manner. At its periphery the cap is provided with teeth 11, projecting at an angle from the plane of the disk, and as seen in Figure 2, these teeth are in position to be embedded in the chair leg 1, or in 100 the wall of its socket 2. With the key anchored in the tenon and the teeth of the cap projecting from the end of the tenon, as in Figure 2, it will be apparent that as the tenon is forced into its mortise or socket 2, 105 these teeth will be caused to penetrate the wood of the chair leg within the socket and spread, as indicated in Figure 4. One end of the anchoring key may be spread to form a head 12 on the cap as in Figures 2 110

and 4 which becomes embedded in the bottom of the mortise, and it will be apparent that as the tenon is forced into its socket the fastening means will join these parts 5 together with a rigid and permanent joint, as in Figure 4.

In Figures 5 and 6 the cap 13, with its opening 10 for co-action with the anchoring key, is fashioned with oppositely extending 10 tongues 14 and 15, struck up or stamped from a blank by suitable dies. The extremities of these oppositely extending tongues are provided with oppositely projecting teeth or spurs 17 and 16. In use 15 the anchoring key is driven into the round 3 to retain the cap 13 on the end of the tenon, and the inwardly projecting spurs 16 of the tongues 14 are forced into the exterior surface of the tenon. As the tenon is 20 forced into its socket, the tongues 15 are spread outwardly, and their teeth 17 are forced into the walls of the socket or mortise, as in Figure 6.

The cap 18 in Figure 7 is adapted for 25 use in a rectangular socket and with a rectangular tenon, instead of with the rounded tenon and socket of Figures 2 and 4. The cap 18 has the central opening 10 for use with the anchoring key, and is provided 30 with oppositely extending tongues 19 and 20 that are formed with oppositely projecting teeth 21 and 22. This cap is used in the same manner as the cap 13.

From the above description taken in connection with my drawings it will be obvious 35 that I have provided an invisible, or interior fastening means for joints of this character, which will insure a rigid and permanent joint between the parts, and will prevent displacement, under ordinary wear for practically an indefinite time. 40

Having thus fully described my invention, what I claim as new and desire to secure by Letters Patent is:

1. An invisible fastening means for a 45 furniture joint comprising a tubular key having a split at one end forming fastening tongues for one piece of the joint, a perforated cap affixed on said key, the other end of the key being split and spread to 50 form retaining tongues for the cap, and angularly disposed retaining teeth on the cap for engagement with the other member of the joint.

2. A fastening means for a furniture joint 55 comprising a tubular key having split ends forming end tongues, said tongues each having beveled edges whereby the tongues are spread outwardly when pressure is applied 60 to the key, a perforated circular disk forming a cap affixed on said key, and angularly disposed teeth on said cap projecting away from said key, for the purpose described.

In testimony whereof I affix my signature.

FOSTER W. DRAPER.
